UNITED STATES PATENT OFFICE.

DANIEL CARLOUGH, OF PATERSON, NEW JERSEY.

CAR-CO尤PLING.

SPECIFICATION forming part of Letters Patent No. 264,926, dated September 26, 1882.

Application filed July 28, 1882. (No model.)

To all whom it may concern:

Be it known that I, DANIEL CARLOUGH, a citizen of the United States, residing at Paterson, Passaic county, State of New Jersey, have invented a new and useful Improvement in Car-Couplings, of which the following is a specification, reference being had to the accompanying drawings, forming a part thereof, in which—

10 Figure 1 is a side view of my newly-invented coupling, showing the parts coupled together. Fig. 2 is a horizontal section of the same. Fig. 3 is a plan. Fig. 4 is a sectional plan of the same. Fig. 5 is a front view of the coupling, and Fig. 6 is a section through the coupling-pins.

15 *a* represents the coupling-box, the front of which is constructed open and bell-shaped, and is thereby adapted to meet any differences in 20 the height of the cars to be coupled, or any lateral differences therein, and guide the coupling-link *c* into engagement with the coupling-pin *b*.

25 *a'* represents that part of the coupling which is to be attached to the cars, which may be attached thereto by any of the known means now employed for that purpose.

30 *a²* represents the opening in the coupling-box. *b* represents the coupling-pin, which is provided with a head of cylindrical form sufficiently large to prevent the escape of the pin through the hole provided for the same in the coupling-box *a*. The coupling-box *a* is dished or hollowed out where the coupling-pin *b* enters the same. The cylindrical part of the pin *b* rests in the dish *i* of the coupling-box *a*, and readily yields to the touch of the coupling-link *c*.

35 *c* represents the coupling-link, which is constructed with an open center, which gives ample space for the coupling-pin *b* to work freely therein. The pivot end of the coupling-link *c* is sufficiently swelled to provide for a suitable hole through the same to accommodate a pivot, 40 *g*, without weakening the link *c*. The pivot *g* works in suitable slots, *f*, formed in the sides of the coupling-box *a*. The pivot *g* may be made like ordinary bolts, kept in position by means of a screw-nut, &c. The free end *e* of the 45 coupling-link *c* is constructed with a feather-edge, which allows the links to operate freely

over each other when coupling the cars. The top of the coupling-box *a* is provided with a slot, *k*, back of the coupling-pin *b*, which admits of the coupling-pin's backward movement when the same is brought into engagement with the free sharpened end of the coupling-link *c*, which carries the pin *b* backward until the link *c* is allowed to pass under the coupling-pin *b*, which, after the solid part of the 55 link *c* has passed in its movement beyond the end of the pin *b*, the coupling-pin *b*, by force of gravity, drops down in the open center of the link *c*, by which action of the pin *b* the cars are coupled together. The bottom of the 60 coupling-box *a* is provided with a receiving-hook, *d*, which holds the coupling-pin *b* in position for draft.

65 Operation: The coupling-box *a* having been attached to the cars by any of the ordinary means employed for that purpose, the link *c* is placed in position in the coupling-box and secured therein by means of the pivot *g* in the slots *f*. The coupling-pin *b* is now put in position, which places the coupling devices in position for automatic action. The cars to be 70 coupled are brought together therefor when the coupling-link *c* presents its sharpened end *e* to the bell-mouth *a'* of the coupling-box, and is directed thereby into engagement with the coupling-pin *b*, which recedes in its engagement with the link *c* until the solid part *e* of the link *c* has passed under and beyond the 75 end of the pin *b*, which releases the coupling-pin *b* from the action of the coupling-link *c*, which causes the pin *b*, by force of gravity, to fall down in the open center of the link *c*, automatically coupling the cars together. The cylindrical form of the head of the coupling-pin *b* facilitates the pin's return to its perpendicular position by relieving the pin from friction on account of its small bearing-surface on the coupling-box. My coupling works equally well with one or two links. The ends of the 80 links being sharpened causes them to pass over and under each other freely. The coupling-pin *b* may be constructed with a point at the bottom to fall in a slot in the bottom of the coupling-box; or an opening may be made in the coupling-box sufficiently large for the coupling-pin *b* to pass through the same, if required, to 85 guard against the pin raising out of position 90 95 100

under heavy draft, &c. The coupling-link *c* is so arranged that it rests on the top of the receiving-hook *d*, and is balanced thereon, but is allowed, by reason of the slot *f*, to yield 5 when it becomes necessary in the operation of coupling, and then returns to its horizontal position.

Having described my newly-invented coupling and its operation, what I claim as my invention, and desire to secure by Letters Patent, is—

The combination of the coupling-box $a a' a^2$, coupling-links *c*, coupling-pin *b*, pivots *g*, slots *f*, slot *k*, dish *i*, latch-hook *d*, and sharpened end *e*, substantially as and for the purpose set forth. 15

DANIEL CARLOUGH.
